UNITED STATES PATENT OFFICE.

FRANK SZ. BUDAJI, OF NEW YORK, N. Y.

CLOTHES-LINE SUPPORT.

Specification of Letters Patent. Patented Oct. 19, 1915.

1,157,502.

Application filed June 25, 1915. Serial No. 36,230.

To all whom it may concern:

Be it known that I, FRANK SZ. BUDAJI, a subject of the King of Hungary, residing at New York city, in the county of Bronx 5 and State of New York, have invented certain new and useful Improvements in Clothes-Line Supports, of which the following is a specification.

This invention relates to certain new and 10 useful improvements in clothes line supports.

The primary object of the device is to provide an efficient means for suspending clothes from a window for the purpose of 15 airing and drying the same and whereby the line full of clothes may be easily withdrawn within the window whenever desired.

A further object of the invention is to provide a laundry device in the nature of 20 an adjustable clothes hanger capable of being substantially positioned interiorly of a building through an open window thereof and then extended out of doors when desired for use in suspending the washed 25 clothes thereon, the arrangement being also capable of providing a plurality of supporting lines.

A still further object is to provide a 30 clothes line construction so adjustably arranged as to allow its complete withdrawal inwardly of a window when not in use and so as to protect the same against the weather although being readily projected outwardly thereof for the ready reception 35 of washed clothes for suspension during the drying operation.

With these general objects in view and others that will appear as the nature of the 40 invention is better understood, the same consists in the novel construction, combination and arrangement of parts hereinafter more fully described, illustrated in the accompanying drawings, and pointed out in the appended claims.

45 In the drawings forming a part of this application and in which like designating characters refer to corresponding parts throughout the several views: Figure 1 is a side elevation of the device projected outwardly of a window of a building. Fig. 2 is a similar view with the device closed and arranged within the window. Fig. 3 is a top plan view of the device as shown in Fig.

1. Fig. 4 is a front elevation of the stationary bracket employed with the device. Fig. 5 is a perspective view thereof de-

tached. Fig. 6 is a perspective view of the forward portion of the adjustable brace, and, Fig. 7 is a perspective view of a line attachment employed with the device.

Referring more in detail to the drawings, it being understood that the invention relates to clothes lines and supports therefor, a window 10 of a building such as a laundry is illustrated having the stationary bracket 11 of the device permanently secured thereto while an upright post 12 is conveniently positioned adjacent the building and provided with a hook 13 and whereby the entire device is operatively supported between the 60 said window and post.

A brace member 14 is arranged for the clothes line having a main bar 15 provided with a gabled top 16 and slidably positioned through the opening 17 in the central arm 18 of the said bracket 11, the said opening corresponding in shape to the said bar. A vertically-arranged cross-piece 19 is carried by the brace bar 15 and is provided with grooved rollers 20 and 21 journaled upon its 75 lower and upper ends respectively. The inner end of the bar 15 is provided with a stop finger 22 for preventing the complete removal of the bar from the said bracket 80 opening.

A pulley rope 23 has one end thereof secured as at 24 to the said cross-piece 19 and then runs over a grooved pulley 25 journaled in the top arm 26 of the stationary bracket 11 and thereafter passes over the 85 said cross-arm upper pulley 21 and is secured as at 27 to a pull cord 28, the said pulley rope extending over a pulley 29 carried by the post hook 13 and having its other end provided with a pulley 30 suspended therefrom.

The pull cord 28 has its free end removably secured to an anchor block 31 carried by the window 10 above the bracket 11. A clothes line 32 formed of an endless rope is 90 passed over the lower brace pulley 20 and the aforementioned rope pulley 30 and then passes over a similar pulley 33 carried by the lower arm 34 of the bracket 11.

With the elements positioned as illustrated in Fig. 2, the clothes line 32 is substantially all inclosed within the window 10 while the brace bar 15 is inwardly positioned within the window and may be retained by means of a cross-pin 35 slidably 105 mounted upon the bracket arm 18 and adapted to traverse the opening 17 thereof.

for engagement with a desired one of the bottom notches 36 of the said brace bar 15. When desired for use, the pull cord 28 is released from its anchor 31 and being pulled, 5 it draws the pulley 30 outwardly to a point adjacent the post pulley 29 and hauling the clothes line 32 with it and when so positioned, the brace 14 may be readily projected outwardly of the window upon first 10 releasing the pin 35 so that the device will assume its operative position as illustrated in Fig. 1. It will be understood however, that a retriever 37 is operatively attached to the end of the pulley rope 23 at its point 15 of attachment to the cross-piece 19 so that any slack occurring in the pulley rope will be automatically taken up. With the line so extended and supported by the brace in the manner described, it will be seen that 20 the endless clothes line 32 may be readily employed for supporting clothes positioned thereon outwardly of the window 10, the line being readily adjusted for supplying and removing clothes in the usual manner 25 by pulling thereon from the window.

In Fig. 7 there is illustrated a manner of supporting a plurality of endless clothes lines 38 which are carried by pulleys 39 journaled at the ends of arms 40 laterally 30 projecting from frames 41. The said frames are provided with supporting cords 42 having hooks 43 for attaching the entire device between the interrupted ends 44 of a clothes line which may take the position of the 35 aforementioned clothes line 32 in the device herein described.

While the forms of the invention herein shown and described are what are believed to be preferable embodiments thereof, it is 40 nevertheless to be understood that various forms, modifications and arrangements of the parts may be made without departing from the spirit and scope of the invention as set forth in the appended claims.

45 What I claim as new is:—

1. A clothes carrier comprising a bracket adapted to be mounted on a window frame having a centrally arranged arm provided with an opening, a bar slidably mounted 50 through the said opening, retaining means for the said bar, a cross-piece at the outer free end of the said bar, upper and lower

pulleys journaled at the ends of the said cross-piece, a post pulley adapted to be mounted on a post positioned outwardly of the window and bar, an endless clothes line carried by the said bracket, lower pulley and post pulley, and an adjusting pull cord for the said clothes line. 55

2. A clothes carrier comprising a bracket 60 adapted to be mounted on a window frame having a centrally arranged arm provided with an opening, a bar slidably mounted through the said opening, retaining means for the said bar, a cross-piece at the outer free end of the said bar, upper and lower pulleys journaled at the ends of the said cross-piece, a post pulley adapted to be carried by a post positioned outwardly of the window and bar, a retriever carried by the 65 said cross-piece, upper and lower pulleys carried by the said bracket, a pulley rope secured at one end to the said retriever and passing over the said upper pulleys of the said bracket and cross-piece and over the 70 said post pulley, and a pulley secured to the other end of the said pulley rope and over which the said clothes line passes. 75

3. A clothes carrier comprising a bracket 80 adapted to be mounted on a window frame having a centrally arranged arm provided with an opening, a bar slidably mounted through the said opening, retaining means for the said bar, a cross-piece at the outer free end of the said bar, upper and lower 85 pulleys journaled at the ends of the said cross piece, a post pulley adapted to be carried by a post positioned outwardly of the window and bar, a retriever carried by the said cross-piece, upper and lower pulleys 90 carried by the said bracket, a pulley rope secured at one end to the said retriever and passing over the said upper pulleys of the said bracket and cross-piece and over the said post pulley, a pulley secured to the 95 other end of the said pulley rope and over which the said clothes line passes, a pull core secured at one end to the said pulley rope and having its other end extending adjacent the said window, and adjustment 100 retaining means for the said bar carried by the said bracket.

In testimony whereof I affix my signature.
FRANK SZ. BUDAJI.
